UNITED STATES PATENT OFFICE.

GEORGE R. HILL, OF ST. LOUIS, MISSOURI.

SASH-LOCK.

SPECIFICATION forming part of Letters Patent No. 658,847, dated October 2, 1900.

Application filed February 16, 1900. Serial No. 5,498. No model.)

To all whom it may concern:

Be it known that I, GEORGE R. HILL, a subject of the Queen of Great Britain, residing at St. Louis; in the State of Missouri, have invented certain new and useful Improvements in Automatic Sash-Locks, of which the following is a full, clear, and exact description, reference being had to the accompanying drawings, forming a part hereof.

10 My invention has relation to improvements in automatic sash-locks; and it consists in the novel arrangement and combination of parts more fully set forth in the specification and pointed out in the claims.

15 In the drawings, Figure 1 is a middle vertical section taken through the window-frame, showing my device in end elevation, the sash being up or closed. Fig. 2 is an elevation of the sash and my device viewed from the inner side of the car, the wall of the box or compartment located below the sill being removed. Fig. 3 is a view similar to Fig. 1, but with the sash lowered into the box. Fig. 4 is a view similar to Fig. 2, but with the sash lowered 25 into the box or compartment below the sill. Fig. 5 is a perspective of the weight and sash-supporting platform carried by it. Fig. 6 is a top plan view of the pocket over which the platform is mounted. Fig. 7 is a perspective view of the weight or bar carrying the locking-latch; and Fig. 8 is a section on line 8 8 of Fig. 4, but with the wall carrying the push-button in place.

30 One object of my invention is to construct a mechanism which will automatically close and lock a car-window sash upon the mere depression of a push-button, which releases the latch by which the sash is held to its open position.

35 A further object is to simplify the mechanism by which the sash is actuated.

In detail the invention may be described as follows:

Referring to the drawings, 1 represents a 40 prevailing type of window-frame, 2 the inner sill thereof, and 3 the outer supporting-ledge for the sash in its closed position. 4 represents the box or compartment below the sill 2, and 5 the passage-way formed for the reception of the sash in its descent into the compartment 4. Located within the box 4 between the sill 2 and the bottom of said box

and disposed adjacent to the sash-guide strips 6 are vertical rods 7, and located exteriorly to the rods 7 and spaced farther apart are similar rods 8. Mounted between the planes of each pair of rods in a bracket 9 is a grooved pulley 10, over which passes a cord or wire 11; one end of which is secured to a weight or bar 12, having terminal loops or tubular enlargements 12', and the other end to a weight or bar 13, having similar terminal tubular enlargements 13'. The bar 12 12' is adapted to travel up and down the rods 7, the tubular ends being passed over the rods and over suitable antifriction-sleeves 14, interposed between the ends 12' and rods 7, the sleeves having their ends burred or expanded to retain them in proper position within the tubular ends 12'. The bar 13 13' is likewise adapted 70 to travel up and down the rods 8, a similar set of antifriction-sleeves 14' being inserted between the rods and the tubular ends 13' of said bar. The bar 13 has a recess 15 cut along one edge thereof and a suitable spring arm or 75 latch 15' secured in the line of said recess, the latch being adapted to engage a keeper 16 on the under side of the sill 2 when the bar is in its elevated position. The latch can be disengaged from its locked position by a spring-controlled push-button 17, mounted in the top of 80 the inner vertical wall of the box 4.

Forming a part of the bar 12 is a vertically-projecting arm or bracket 18, provided with an outwardly-projecting pocket 19, the lateral 85 walls of the pocket serving to support a pin 20, to the outer projecting ends of which are pivotally secured the lugs 21 of a tilting sash-supporting platform 22, which normally rests upon the upper end of the bracket 18. Coiled 90 about the pin 20 within the pocket 19 are the arms of the looped-wire spring 23, the ends of the arms bearing against the outer wall of the pocket, the loop under the circumstances having a tendency to tilt the platform 22 to an 95 open position. (See Fig. 5.) The platform closes to a horizontal position under the weight of the sash while the latter is in the box 4, (see Figs. 3 and 4,) the sides of the loop being received in depressions 24, formed along 100 the upper edge of the bracket 18, to allow the platform to assume a perfectly-horizontal position.

The operation of the device is as follows:

The bar 13 13' more than balances the combined weights of the bar 12 12', platform 22, and sash S, suspended from the cord 11. If the base of the sash is pulled outwardly, so 5 as to rest upon the platform, (see Fig. 1,) and then forced downward, so as to depress the platform to the bottom of the box 4, the bar 13 13' will be raised, (see Fig. 3,) the latch 15' engaging the keeper 16 and allowing the window- 10 sash to remain at the bottom of the box 4. When the latch is disengaged by the push-button, (see dotted position, Fig. 8,) the weighted bar 13 13' will drop down along the rods 8 8', raising the window back to its original position. 15 When the base of the sash is opposite the upper surface of the ledge 3, by which time the platform 22 emerges from the box 4, the spring-loop 23 by its resiliency tilts the platform 22 to an inclined position, the base of 20 the sash being thus forced outwardly upon the ledge 3, designed for its permanent reception. (See dotted position, Fig. 1.)

It is understood that I do not limit myself to the precise details here shown, as the same 25 may be departed from without affecting the spirit of my invention.

Having described my invention, what I claim is—

1. In a sash-lock, a suitable sash-supporting 30 platform occupying a position adjacent to the lower edge of the sash for the raised position of the latter, the sash and platform being adapted to be lowered and the parts locked in their depressed position, and to automatically resume their original position upon the parts being released from the locking device, substantially as set forth.

2. In a sash-lock, a suitable tilting platform for the support of the sash, means for lowering and raising the said platform, and retaining the same in either of its extreme positions, and devices for tilting the platform when in one of its extreme positions for throwing the sash off from the supporting-surface of said 45 platform, substantially as set forth.

3. In a sash-lock, a suitable platform for the support of the sash, a weight or bar to which said platform is secured, rods for guiding the bar in its vertical movements, a second weight or bar, guide-rods for the same, a pulley, a cord passing over the pulley and having its ends secured to the respective weights aforesaid, a locking device for said second weight or bar, and means for disengaging the locking device, substantially as set forth.

4. In a sash-lock, a suitable platform, lugs

for the same, a bracket, a pocket for said bracket, a pivotal pin passing through the lugs and through the lateral walls of the pocket, 60 a loop having arms coiled about the pin within the pocket, the loop normally bearing against the under surface of the platform and tending to tilt the same, depressions formed in the bracket for receiving the sides of the loop 65 to insure a true horizontal position for the platform when supporting the sash, means for raising and lowering the platform, a supporting-ledge for the sash, the platform being adapted to throw the sash laterally upon the 70 ledge when the lower edge of the sash comes opposite said ledge, substantially as set forth.

5. A sash-lock comprising a platform for the sash, a compartment for receiving the sash located below the window-sill, a weight 75 having tubular enlargements carrying said platform, antifriction-sleeves within the enlargements, guide-rods over which said sleeves pass, located below the sill, a second weight or bar having tubular enlargements and similar sleeves and guide-rods therefor, a pulley mounted below the sill, and having a cord passing over the same with its ends secured to the respective weights, a recess formed in the second weighted bar, a latch located in 80 the path of such recess, a keeper in the sill for engaging the latch, a push-button carried by the inner wall of the compartment below the sill, and operating through said recess and adapted to engage the latch, the parts operating substantially as and for the purpose set forth.

6. In a sash-lock, a suitable window-frame having the usual inner sill and outer supporting ledge for the sash, means for depressing 95 the sash below sill and ledge and locking the parts in said position, and devices for disengaging the parts from their locked position, and raising the sash and depositing the same automatically upon the ledge, substantially 100 as set forth.

7. In a sash-lock, a suitable window-frame, having the usual inner sill and outer sash-supporting ledge, means for permitting the depression of the sash below the sill and ledge, 105 and mechanical devices for automatically returning the sash to its original position, substantially as set forth.

In testimony whereof I affix my signature in presence of two witnesses.

GEORGE R. HILL.
